DESIGN FOR A PARKING METER CASING

Louis V. Lucia, West Hartford, Conn., and Harmon D'Agostino, New York, N. Y., assignors to The Standard Meter Corporation, Hartford, Conn., a corporation of Connecticut

Application July 22, 1937, Serial No. 70,581

Term of patent 3½ years

To all whom it may concern:

Be it known that we, Louis V. Lucia and Harmon D'Agostino, citizens of the United States, residing respectively at West Hartford, in the county of Hartford and State of Connecticut, and New York, in the county of New York and State of New York, have invented a new, original, and ornamental Design for a Parking Meter Casing, of which the following is a specification, reference being had to the accompanying drawing, forming part thereof.

Figure 1 is a front elevational view of a parking meter casing embodying our invention.

Figure 2 is a side elevational view, partly in section.

Figure 3 is a rear view of the same.

We claim:

The ornamental design for a parking meter casing, substantially as shown.

LOUIS V. LUCIA.
HARMON D'AGOSTINO.
